UNITED STATES PATENT OFFICE.

GUIDO FORNACA, OF TURIN, ITALY.

APPARATUS FOR USE IN RECTIFYING CYLINDER BORES.

Application filed July 18, 1924, Serial No. 726,849, and in Italy December 20, 1923.

This invention relates to apparatus for use in rectifying cylinder bores, of the kind having a plurality of grinding or cutting tool spindles, one for each cylinder, adapted 5 to be given combined movements of rotation and orbital revolution.

I provide an improved and simplified apparatus of this kind characterized by a central operating arrangement for producing 10 these movements. Said arrangement comprises, a shaft operatively connected to the tool spindles and mounted in a sleeve forming part of a carriage supporting the spindles.

15 The apparatus may be applied direct to the usual rectifying machine, having a head which provides for rotation of the shaft and eccentric or orbital revolution of the sleeve, after dismounting the single mandrel tool 20 holder with which such machines are provided; or it may form part of a specially constructed machine.

The accompanying drawing shows, by way of example, a form of the apparatus 25 suitable for rectifying simultaneously the four cylinders of a mono-block internal combustion engine.

Fig. 1 is a front elevation of the apparatus shown partly in section on the line 30 1—1 of Fig. 2.

Fig. 2 is a section on the line 2—2 of Fig. 1.

Fig. 3 is a section on the line 3—3 of Fig. 1.

35 Fig. 4 is a diagrammatic longitudinal vertical section of the apparatus applied to an ordinary grinding machine.

In the drawing, 1 indicates a frame upon 40 which is mounted for vertical sliding movement a carriage 2 balanced by means of a counterweight 3 movable on an arm of a lever 15 hinged at 16 to the support 4 and having its other arm connected, by means of a link 17, to the carriage 2. Mounted for 45 horizontal sliding movement on the carriage 2 is an auxiliary carriage 5 retained in place by strips 6, and projecting from the carriage 5 are sleeves 7 intended to support the shafts 8 of the grinding tools. The carriage 5, being combined with the carriage 2, can 50 be displaced in any direction while remaining parallel to itself, after the manner of an Oldham joint.

The shafts 8 are mounted in adjustable 55 sleeves 18; the inner end 19 of each shaft is square in cross section and engages in a

cavity of corresponding form in a toothed wheel 9 carried by shafts 20. The wheels 9 engage with transmission pinions 10; moreover the intermediate wheels 9 engage 60 with a main driving wheel 11, which latter is keyed on a shaft 12 mounted in a sleeve 13, while at the outer ends said shafts 8 carry the grinders 14.

Referring especially to Fig. 4 showing 65 diagrammatically a grinding machine provided with this arrangement the sleeve 13 is eccentrically connected by means of sleeve joint 21 with the head 22 rotatably mounted in the support 23 and carrying at its 70 other end a pulley 28 having the same eccentricity as the attachment of the sleeve 13. The shaft 12 in its turn is connected with the shaft 24 of the grinding machine passing through an eccentric hole of the 75 head 22 and carrying the driving pulley 25. The cylinder 26 to be rectified is mounted on a carriage 27 movable in an axial direction, of the grinding machine.

Owing to the eccentricity of the head 80 of the rectifying machine there is imparted to the sleeve 13 a movement of revolution which movement is transmitted to the carriage 5, the sleeves 7, all the shafts 8, and the gears 9. At the same time the latter 85 receive from the machine shaft 24 connected to 12 a rapid movement of rotation. The grinding tools keyed on the shafts 8 are thus actuated by two combined movements of rotation and revolution. The orbits of rev- 90 olution described by the sleeves 7 (and by the grinding tools) of necessity are all equal and their diameter will be determined by the eccentricity of the machine head and it will be adjustable if the eccentricity is ad- 95 justable.

The apparatus is described and represented in the drawing for operation from a horizontal shaft, but it may be arranged for operation from a vertical shaft and the 100 latter arrangement may even be the most rational if a machine is expressly built for the purpose of carrying out the invention.

In this case the counterweight 3 may be omitted, as the carriages will then move 105 in horizontal planes. Of course, other modifications can also be made without departing from the spirit or scope of the invention.

What I claim is:

1. An apparatus for rectifying a plural- 110 ity of cylinder bores comprising a casing, a plurality of spindles carrying abrasive

wheels mounted in the latter, one for each cylinder, and a central operating mechanism for simultaneously imparting a rotary and orbital revolution to the spindles.

5. 2. An apparatus for rectifying cylinder bores, comprising a plurality of spindles carrying abrasive wheels one for each cylinder, a carriage supporting the spindles, a sleeve forming part of the carriage, a shaft 10 rotatably mounted in the sleeve operatively connected to the spindles, and means for imparting an orbital movement to the sleeve.

3. An apparatus for rectifying cylinder bores, comprising two carriages movable in 15 directions perpendicular to each other, a plurality of spindles carrying abrasive wheels mounted in one of the carriages, a sleeve forming part of said carriage adapted to be rotated eccentrically to produce orbital 20 revolution of the spindles, gears connecting

the spindles for simultaneous rotation, and a shaft rotatably mounted in the sleeve for transmitting rotary motion to all the spindles through said gears.

4. An apparatus for rectifying cylinder bores comprising a vertically movable carriage, an auxiliary carriage, horizontally movable on the latter, a plurality of spindles carrying abrasive wheels journaled in the auxiliary carriage, a pinion on each spindle, a sleeve mounted in the auxiliary carriage, a shaft rotatably journaled in the sleeve, a gear on the shaft, gearing operatively connecting said gear with the pinions, and means for imparting an orbital movement 25 to said sleeve.

In testimony that I claim the foregoing as my invention, I have signed my name.

GUIDO FORNACA.
